UNITED STATES PATENT OFFICE.

ALVA AYERS, OF PAYSON, OKLAHOMA TERRITORY.

FLOOR-SET.

No. 847,272.

Specification of Letters Patent.

Patented March 12, 1907.

Application filed December 21, 1905. Serial No. 292,741.

To all whom it may concern:

Be it known that I, ALVA AYERS, a citizen of the United States, residing at Payson, Lincoln county, in the Territory of Oklahoma, have invented a new and useful Floor-Set, of which the following is a specification.

The object of this invention is to provide an implement for facilitating the laying of floors.

10 The accompanying drawings illustrate the invention.

Figure 1 is a perspective view of a floor-set embodying the invention. Fig. 2 is a longitudinal mid-section of the same in position 15 for setting a floor, a fragment of which is shown.

10 The floor-set comprises a body 1 and handle 2, the body being constructed with a poll 3 and a block 4, said block having a grooved 20 setting-face 5 and a flat base 6 at one edge and the poll and handle being aslant relative to said base. The body 1 is provided at the bend between the poll and the base with a slanting handle-socket 7, which slants upward away from the poll and toward the 25 grooved face 5, the groove 8 in which is adapted to receive the tongue of the flooring 9.

20 In the drawings, 10 represents subflooring 30 or a joist on which the flooring 9 is being laid. The poll 3 is preferably provided with a socket 11, in which a buffer 12 is seated.

13 indicates a shank-boss extending up from the implement at the bend 14 thereof.

35 In practical operation the workman will grasp the handle 2 in his left hand and will hammer the poll to drive the flooring into place, the grooved face 5 being brought along the tongued face of the floor to be laid.

40 It is obvious that the tool may be made of any suitable metal or other desired material, metal being preferred. The tool is preferably so constructed that the center of gravity lies at such a point as to cause the tool to rest upon its base 6 when left free, so that 45 the handle 2 is always in position to be grasped by the workman.

15 designates a shoe on the buffer 12 to receive the impact of the blows. The buffer 12 may be made of wood, fiber, or any other 50 suitable material.

What I claim is—

1. A floor-set comprising a body and a handle, the body being constructed with a block and with a poll set aslant thereon, said 55 block being provided at one edge with a grooved face.

2. A floor-set comprising a bent block provided in its bend with a slanting handle-socket and provided on one edge with a 60 grooved face.

3. A block provided on one edge with a hollow poll, and on the other edge with a groove.

4. A bent block provided on one side of 65 the bend with a hollow poll, and on the other side of said bend with a grooved face, a buffer in said poll and a handle for handling the block.

5. A floor-set comprising a block having a 70 base, a grooved face at one edge and a socketed poll at the other edge, a buffer in said poll, and a slanting handle.

6. A floor-set comprising a block having a base, a setting-face at one edge thereof, a 75 poll at the other edge thereof, and a handle between the poll and the said face, the poll and base being aslant relative to each other.

7. A floor-set comprising a body and a handle, the body being constructed with a 80 poll and a block, said block having a grooved face and a flat base at one edge, and the poll and the handle being aslant relative to said base.

In testimony whereof I have hereunto set 85 my hand, at Los Angeles, California, this 14th day of December, 1905.

ALVA AYERS.

In presence of—

JAMES R. TOWNSEND,
JULIA TOWNSEND.
